UNITED STATES PATENT OFFICE.

EDSON POTTER, OF GREENSBURG, INDIANA.

MAIL-BAG CATCHER.

SPECIFICATION forming part of Letters Patent No. 678,278, dated July 9, 1901.

Application filed February 26, 1901. Serial No. 48,905. (No model.)

To all whom it may concern:

Be it known that I, EDSON POTTER, a citizen of the United States, residing at Greensburg, in the county of Decatur and State of Indiana, have invented certain new and useful Improvements in Mail-Bag Catchers, of which the following is a specification, reference being had therein to the accompanying drawings.

10 This invention relates to new and useful improvements in mail - bag catchers or receivers, and more particularly to that class adapted to be used upon mail-cars.

15 The primary object of the invention is to provide a device of this character adapted to receive the mail-bag from a crane while the car is in motion and to so clamp the same as to prevent its removal until brought to the proper position within the car.

20 With this and other objects in view the invention consists in the novel construction and combination of parts hereinafter more fully described and claimed and illustrated in the accompanying drawings, showing the preferred form of my invention, and in which—

25 Figure 1 is a perspective view of the device, showing the same in position upon a mail-car. Fig. 2 is a section through the catcher, showing the same in position to receive a mail-bag. Fig. 3 is a detail view of the eccentrics upon the supporting-rod and of the locking-yoke of the device. Fig. 4 is a section through the fork of the catcher, showing the same locked in closed position. Fig. 5 is a detail view of 35 the locking-yoke, and Fig. 6 is a transverse section through the eccentrics upon the supporting-rod.

30 Referring to the figures by numerals of reference, 1 is a casting adapted to be secured in any suitable manner to one side of a car-door and having a bolt 2 revolubly mounted therein. The upper end 3 of this bolt is enlarged, so as to bear upon the casting, and a rod 4 is secured thereto and extends laterally therefrom. This rod is adapted to extend across the door, and the free end thereof normally rests between ears 5, extending from a plate 6, secured to the side of the door farthest removed from the casting 1. A pin 7 is 45 adapted to be inserted into perforations formed within the ears and serves to prevent

the rod 4 from swinging outward upon its pivot.

50 The rod 4 is cut away at a point preferably adjacent to the middle thereof, as shown at 55 8, forming an eccentric for the purpose hereinafter more fully described, and eccentric collars 9 are arranged at opposite sides of the eccentric 8. These eccentrics are inclosed by and revoluble within a pipe-cross 10, which 60 is screwed upon threaded collars 11, arranged upon the rod 4 at opposite sides of the eccentrics 9. Pins, as 12, may be employed for preventing the cross from revolving upon the threaded collars after once being placed into 65 engagement therewith.

70 Extending from one of the remaining arms of the cross 10 is a short tube 13, within which is revolvably mounted a hollow stem 14, having an annular groove 15 therearound, which 75 is adapted to receive a key which serves to prevent the removal of the stem. This stem is arranged at one side of a curved plate 16, forming the yoke of the catcher proper, and an arm or tine 17 extends from one end of the 80 plate, while a second arm or tine 18 is hinged to the remaining end. A curved plate 19, preferably L-shaped in cross-section, is secured to this arm 18 and lies within and normally overlaps one edge of the curved plate 85 or yoke 16. This inner plate 19 is provided at its free end with a recess 20, formed within the inner face of said plate, and a spring-strip 21 is suitably secured therein and is adapted to engage a shoulder 22, formed within the adjacent face of the yoke 16.

90 The shoulder 22 is arranged adjacent to the passage through the stem 14, and slidably mounted within this stem is a pin 23, having laterally-extending guide-studs 24, which are 95 slidably mounted within slots formed within the stem 14 at the inner end thereof. The inner end of the pin 23 is adapted to contact with the intermediate eccentric 8, and it will therefore be understood that when the cross 10 and the collars 11 are revolved upon the rod 4 this pin will be forced longitudinally within the stem.

100 The inner end of the stem 14 is flattened upon opposite sides, as at 25, so as to be engaged by the ends of a yoke 26, which extends over the rod 4 and lies between the ec-

centric collars 9. Shoulders 27 are formed at the inner end of the yoke 26, and these are adapted to ride upon the eccentrics 9 and release the yoke from engagement with the 5 end of the stem 14. A stem 28 is arranged at the inner end of the yoke 26, and this is slidably mounted within a tube 29, which extends from the remaining arm of the pipe-cross 10. A coil-spring 30 incloses the stem 10 28 and bears at opposite ends upon the tube 29 and the shoulders 27, respectively, and this spring serves to hold the shoulders in contact with the eccentrics 9 at all times.

The tube 29 may be provided at its outer 15 end with a suitable handle 31, of wood or other material, whereby the apparatus may be readily manipulated.

When it is desired to use the catcher herein described, the same is swung into a horizontal position, as shown in Fig. 1, by bearing down upon the handle 31. The tines or arms are opened out, as will be hereinafter more fully described, and the device is then in condition for use. The tines are held in 25 a plane with the rod 4 by the yoke 26, which engages the end of the stem 14, the eccentrics being so constructed as to permit the yoke to engage said stem when horizontal. At the same time the pin 23 lies at a point 30 removed from the shoulder 22. The positions of the parts as above described are illustrated in Fig. 2 of the drawings. As soon as the tines are brought into contact with the mail-bag, which has been placed in position upon 35 a crane of any suitable construction, the head of the bag will swing the curved plate 19 backward, thereby swinging the tines together and firmly grasping the bag. Then as the tines reach the limit of the inward movement 40 the spring-strip 21 will drop into engagement with the shoulder 22 and lock the tines together. At the same time the weight of the bag will cause the cross-pipe 10 and the parts connected thereto to revolve upon 45 the rod 4, thereby swinging the yoke 16 downward and inward, and during this movement the eccentrics 9 will force the yoke 26 away from the stem 14 and permit the tines to swing into the car, their stem 14 serving 50 as a pivot. As soon as the inward movement of the tines occurs the intermediate eccentric 8 will contact with the pin 23 and force the same against the spring-strip 21, pressing said strip out of the path of the shoulder 22 55 and permitting the lower tine 18 to swing open. The bag can then be removed and the operation above described repeated.

In the foregoing description I have shown the preferred form of my invention; but I do 60 not limit myself thereto, as I am aware that modifications may be made therein without departing from the spirit or sacrificing the advantages thereof, and I therefore reserve the right to make such changes as fairly fall 65 within the scope of my invention.

Having thus fully described my invention,

what I therefore claim as new, and desire to secure by Letters Patent, is—

1. In a device of the character described, the combination with a supporting-rod; of a 70 tine suspended from and adapted to swing upon, said rod, a second tine hinged to the first-mentioned tine, a catch for locking the tines in closed position, and means operated by the supporting-rod, for automatically releasing said catch.

2. In a device of the character described, the combination with a supporting-rod; of a yoke suspended from, and adapted to swing upon, said rod, a tine extending from the 80 yoke, a plate hinged to the yoke and adapted to swing thereinto, a tine extending from the plate, a catch upon the plate adapted to engage the yoke and lock the tines in closed position, and means operated by the supporting- 85 rod, for releasing the catch from the yoke.

3. In a device of the character described, the combination with a supporting-rod having an eccentric thereon; of a sleeve revolvable upon the rod and inclosing the eccentric, 90 a stem revolvable within the sleeve, a pin slidably mounted within the stem and adapted to be operated by the eccentric, a yoke to the stem, a plate hinged to the yoke and adapted to swing thereinto, tines extending from the 95 plate and yoke, and a catch upon the plate adapted to engage the yoke, said catch being adapted to be released by the pin.

4. In a device of the character described, the combination with a supporting-rod, of an 100 eccentric thereon, a sleeve revolvable upon the rod and inclosing the eccentric, a stem revolvable within the sleeve, tines extending therefrom, a yoke slidably mounted within the sleeve and adapted to engage the stem, shoulders to the yoke, means for holding the shoulders normally in contact with the eccentric, 105 said eccentric being adapted to automatically release the yoke from the stem of the tines.

5. In a device of the character described, 110 the combination with a supporting-rod having an intermediate eccentric and an oppositely-arranged eccentric at each side thereof; of a sleeve revolvable upon the supporting-rod and inclosing the eccentrics, a tubular stem 115 swiveled within the sleeve, a yoke secured thereto and having a shoulder formed therewith, a plate hinged to the yoke, a spring-strip secured thereto and adapted to automatically engage the shoulder, tines extending 120 from the yoke and plate, a pin slidably mounted within the stem and adapted to be operated by the intermediate eccentric and to release the spring-strip from the shoulder, and guides for said pin.

In testimony whereof I affix my signature 125 in presence of two witnesses.

EDSON POTTER.
